UNITED STATES PATENT OFFICE.

LOUIS WAGNER AND JOHN MARR, OF BALTIMORE, MARYLAND.

BUNGING APPARATUS.

SPECIFICATION forming part of Letters Patent No. 516,668, dated March 20, 1894.

Application filed June 24, 1893. Serial No. 478,692. (No model.)

To all whom it may concern:

Be it known that we, LOUIS WAGNER and JOHN MARR, citizens of the United States, residing at Baltimore, in the State of Maryland,

5 have invented certain new and useful Improvements in Bunging Apparatus; and we do declare the following to be a full, clear, and exact description of the invention, such as will enable others skilled in the art to which it 10 appertains to make and use the same.

In what may be termed the second fermentation of beer for the purpose among other things of charging it with carbonic-acid gas to give it the proper life, the beer is confined 15 or "bunged" in large and strong casks. This operation prevents the escape of gas generated in the beer, or permits the escape of the excess of gas only. It is also found desirable and economical to distribute the excess of gas 20 from any cask or casks among other casks in which the fermentation is slower and of less amount. For this purpose the said casks are connected with a common gas conduit through which the carbonic-acid may pass in the direction of the least pressure.

Our present invention relates to apparatus of this character and has for its objects to permit the gas to pass from any cask containing an excess of the same, but always to maintain 30 in said cask all gas generated therein until the maximum predetermined pressure is attained. Also to permit the entrance of gas provided that the pressure within the cask is less than the pressure in the gas conduit with 35 which the gas is connected. Also to provide, outside of or independent of the gas conduit which extends from one to another of the individual gas pipes of the several casks, a pressure regulator which may consist of a 40 head or column of water, a spring controlled valve, or other equivalent device. Also to enable casks in various different positions, for instance in two or more rows at right angles to each other, to be conveniently connected 45 with the main gas conduit.

With such objects in view our invention consists in the parts and combinations thereof hereinafter set forth and claimed.

In order to make the improvements more 50 clearly understood we have shown in the accompanying drawings means for carrying the same into practical effect, without however

limiting our invention in its practical applications to the particular construction which, for the sake of illustration, we have delineated.

In said drawings:—Figure 1 is an elevation showing a series of casks having applied thereto a bunging apparatus embodying our improvements. Fig. 2 is a side view, partly 60 in section, and on a larger scale of that portion of the apparatus which pertains to a single cask. Fig. 3 is a plan view, partly in section, of the same. Figs. 4, 5, and 6 are sectional views on lines IV—IV, V—V and 65 VI—VI— of Fig. 3. Fig. 7 is a perspective view illustrating the construction of the joints of the connecting gas pipe.

Referring to the drawings 1 indicates the beer casks in which the secondary fermentation is to be performed, which are frequently termed shavings-casks, arranged in any suitable number and position for connection with the bunging apparatus. The latter comprises a main gas pipe 2 which extends in a substantially horizontal direction through the cellar, and which is connected at suitable intervals with the individual bunging devices of the several casks.

Each bunging device 3 comprises a bung or 80 equivalent means for making gas tight the cask to which the device belongs, and a conduit leading from the interior of the cask through the said bung and adapted to permit the ingress or egress of gas according to the 85 direction of the pressure. Such conduit may also be employed for racking off the beer when sufficiently fermented.

We may here state that the bung and conduit employed with the rest of our improved 90 apparatus may be of any desired and suitable character and forms no necessary part thereof. We however have illustrated and preferred to employ the vent bung described in detail in and constituting the subject matter 95 of the application of Louis Wagner of even date herewith, (Serial No. 478,593, filed June 23, 1893.)

In the drawings 4 indicates the bung and 5 the sleeve or conduit extending therethrough 100 to the interior of the cask and provided with a suitable cock 7. At the upper end of the sleeve 5 we prefer to mount a pressure gage 8 by which, when the apparatus is in operation

the pressure in each cask is indicated. 9 is a screw-threaded extension of the sleeve 5 provided with a passage 10.

11 indicates a valve chamber provided with 5 a screw-threaded aperture 12 with which is adapted to be connected, by a T or other coupling 13, the main gas pipe 2. Leading from the aperture 12 the chamber 11 is provided with a passage 14, leading to a space 15 10 provided with a valve seat 16.

17 is a valve fitting said seat and adapted to permit the passage of gas through the way 14 in the direction of the pipe 2. This valve is controlled by a suitable opposing pressure, 15 as by that of a spring 18, so as to permit the said escape of gas from the cask only when the pressure in the latter exceeds the said opposing pressure. The latter should be capable of regulation as to its amount and to this 20 end we mount in a case 19 screwed upon the chamber 11 a vertically adjustable plunger or screw 20 adapted to engage the spring 18 and compress the same more or less upon the valve 17 according to the amount of pressure 25 which it is desired to maintain in the cask. On the opposite side of the valve 17 a passage 22 forms a continuation of the passage 14 and leads to a space 22^a. The latter has a short passage 23 leading to a valve seat 24 and controlled by a valve 25 on said seat. This latter valve is also controlled as to the amount of 30 pressure which will open it, as for instance by a spring 26, which in practice is adjusted to such tension that the valve 25 will open only 35 under a somewhat greater pressure than the valve 17. Above the valve 25 a passage or pipe 27 serves as an escape for the surplus gas, which latter it is preferable to conduct out of the cellar into the open air, or into a 40 receiver in which it may serve any useful purpose, by extending the pipe 27 as indicated in the drawings.

28 is a valve case screwed to or formed with the chamber 11 and provided with a shut off 45 cock 29 which is to be closed when it is desired to cut off a cask from the rest of the apparatus for racking off or other purpose.

30 is a screw-threaded coupling sleeve connected with the valve case 28 and adapted to 50 be connected with or disconnected from the extension 9 of the conduit 5.

31 is a passage also leading from the aperture 12 of the chamber 11 to the space 22^a from whence it may have communication with 55 the cask through the parts 28, 30 and 5.

32 is a valve seat in the passage 31 on which fits a check valve 33 adapted to permit the entrance of gas into the cask from the pipe 2 whenever the pressure in the latter prepon- 60 derates, but which will not allow of any escape or passage of gas from the cask.

34 is a plug which closes the upper end of the chamber in which the check valve is situated and which may be removed for assem- 65 bling or cleaning the parts. The check valve 33 may be kept normally upon its seat 32

either by gravity as illustrated or in any equivalent way.

It will be observed from a consideration of the construction and operation of the apparatus as thus far described that the pressure in the main gas pipe can never exceed by any material amount that in the various casks connected with it. On the other hand the carbonic-acid gas pressure in each cask will accumulate up to the limit which will operate its spring controlled valve 17, and upon exceeding such limit the extra quantity of gas will pass through said valve and into the main gas pipe, and thence through the valve 33 of 80 the bunging device pertaining to any cask the pressure in which is less than will be the pressure in said main pipe after the latter shall have received the said extra quantity of gas. In the case of excessive pressure, 85 above the limit of safety, or above the limit for which the valve 25 is adjusted, the latter will be operated and the excess of gas will pass away through the passage or pipe 27 and out of the cellar into the atmosphere or into 90 any receiver with which the said pipe, may be, for economical purposes, connected.

While it is convenient to provide each of the bunging devices with the escape valve 25, it will be observed that it is not necessary 95 that the valve on each of a connected series of bunging devices should be operative. One of such valves only, whichever may be most convenient, need be connected with the pipe 27, and the adjusting screws of each of the 100 other valves may be turned downward so as to compress their valves and render them tight and inoperative. In such case when there is an accumulated pressure in any cask at a distance from the valve 25 which is so 105 connected with the escape passage 27, the valve 17 in the bunging device of the cask having such excessive pressure will be operated, and the excess of gas will pass into the main pipe 2, from which it will, if it finds no 110 exit into a cask having a low pressure, actuate the check valve 33 which is contiguous to the passage or pipe 27 and will pass through the valve 25 of the latter and escape.

If there should be a leak in any one of the 115 casks connected with the main pipe 2, or if there should be no fermentation of its contents, all the gas could, under the old system, pass freely from the other casks into the main pipe 2 and would be at liberty to enter such 120 leaky cask and escape therefrom, but it will be observed that each of the other casks is so controlled by its valve 17 that its contents can never lose any of the carbonic-acid gas generated therein until such gas shall have accumulated beyond the desired quantity and shall have exerted a sufficient pressure to pass the valve 17. In such case the escape of the excess of gas from the cask is desirable, and will not leave the contents of the cask in 125 a flat condition as would be the case if the casks were not individually controlled and a 130

leak should exist anywhere in the series or in their connecting pipe.

It is often desirable to connect the bunging apparatus with one or more casks which are not situated in the same row or straight line with the other casks. As it is not practically possible to move such casks into line with the main pipe 2, we have adapted the latter to be so shifted and modified as to its position as to admit of bringing into the series of bunged casks any individual receptacle which may be thus out of line. To this end the pipe 2 at or near each bunging device 3 is provided with a movable section 35 which is united with that portion of the pipe 2 contiguous to the bunging device by means of a horizontal joint 36 which permits the section 35 of the main conduit to be turned upward or downward to the desired degree. The said section 35 is at its other end connected with the main portion of the pipe 2 by a vertical joint 37. By the operation of these two joints it will be observed that the said main portion of the pipe 2 can be extended in any desired direction and at any inclination either horizontal or vertical, so as to reach the casks desired to be included in the bunged series.

The pipe 2 is for the greater portion of its length made of considerable diameter, say two or two and a half inches, as indicated at 38, thereby enabling it to contain a considerable amount of gas without the necessity of employing a receiver.

Having thus described our invention, what we claim is—

- 35 1. A bunging device adapted to be interposed between a gas conduit and the cask to be bunged, provided with two independent passage ways, a check valve in one of said 40 passage ways adapted to operate to permit ingress of gas to the cask, and a pressure controlled valve in the other passage way adapted to operate upon a preponderance of pressure in the cask, substantially as set forth.
- 45 2. A bunging device adapted for connection with a gas conduit, and with a cask, provided with a check valve to permit the ingress of gas to the cask and prevent the egress therefrom, an automatic valve adapted to open to 50 permit such egress, and means acting to keep this automatic valve normally closed for controlling it so as to prevent its opening excepting under a predetermined accumulated pressure in the cask, substantially as set forth.
- 55 3. A bunging device having a check valve adapted to permit the ingress of gas into a cask and to prevent the egress of the same, a pressure controlled valve normally closed and

adapted to open upon the accumulation of the predetermined amount of gas in the cask to 60 permit the egress of the same, and a second pressure controlled valve independent of the main gas conduit and communicating with the passage way of the bunging device and adapted to operate at a pressure exceeding 65 that at which the first pressure controlled valve operates, substantially as set forth.

4. In a bunging device the combination with a suitable casing or chamber having an orifice adapted to be connected with a gas conduit 70 and a second orifice adapted to be connected with a cask, of the pressure controlled valve 17, the check valve 33 independent of the first mentioned valve, and independent passage ways in the said bunging device controlled by 75 the said valve as described, and both extending from the first mentioned orifice to the second mentioned orifice, substantially as set forth.

5. A bunging device having a suitable chamber or casing, an outwardly opening spring-controlled check valve 17 therein, the inwardly opening check valve 33 independent of the valve 17, and a second pressure controlled valve 25 adapted to operate only at a higher 85 pressure than that which will actuate the valve 17, as and for the purposes described.

6. The combination with a plurality of casks, of suitable vent bungs therein, sleeves or conduits 5 in the said bungs, a series of 90 bunging devices connected with said sleeves and provided each with a check valve 33, a pressure-controlled exit valve 17, a main gas pipe or conduit connected with the said bunging devices beyond the said valves, and a 95 pressure-controlled valve or escape 25 independent of the main gas conduit and connected with one of said bunging devices, substantially as set forth.

7. A bunging device having the valve chamber 11, a passage way therethrough controlled by a valve 17, means for keeping the latter yieldingly upon its seat, a check valve 33 controlling a second passage way through the said valve chamber, a second pressure-controlled valve 25 operating at a different degree of pressure from that actuating the said valve 17, and a cut off cock 29, substantially as set forth.

In testimony whereof we affix our signatures in the presence of two witnesses.

LOUIS WAGNER.
JOHN MARR.
